UNITED STATES PATENT OFFICE.

LEO J. STYSLINGER, OF PITTSBURGH, PENNSYLVANIA, ASSIGNOR TO AUTO TRUCK EQUIPMENT COMPANY, OF PITTSBURGH, PENNSYLVANIA, A CORPORATION OF PENNSYLVANIA.

TRUCK BODY.

Application filed November 6, 1923, Serial No. 673,099. Renewed January 28, 1928.

The present invention relates broadly to vehicle bodies, and more particularly to bodies adapted for use with motor trucks used for hauling bulk material.

5 It has heretofore been customary in the art to construct truck bodies of two general types, one being substantially all metal, and the other being mainly of wood with metal reinforcements or irons. The all-metal types 10 have been constructed to hold the maximum load of the lighter materials usually handled. This has required high sides and steel bodies, which are very objectionable where heavier bulk material, such as ores, wet sand and the 15 like, are being handled.

The bodies of the other type have been constructed in such manner that the wood carries the metal, the metal being applied merely for reinforcing after the wooden frame has 20 been completed. Consequently, each time a body became worn out a complete new body had to be made and then ironed. In case of 25 repairs, considerable difficulty has been encountered.

25 In accordance with the present invention, the disadvantages of both types of trucks are overcome, and there is provided a sub-frame adapted to have applied thereto either a suitable wooden body or a metal body of 30 usual or novel construction.

In the accompanying drawings, there are shown for purposes of illustration only, certain preferred forms of the present invention, it being understood that the drawings 35 do not define the limits of my invention, as changes in the construction therein disclosed may be made without departing from the spirit of the invention or scope of my broader claims.

40 In the drawings:

Figure 1 is a transverse sectional view through a body of the wooden type constructed in accordance with the present invention;

45 Figure 1^a is a side elevation of a portion of the body illustrated in Figure 1;

Figure 2 is a bottom plan view of the construction illustrated in Figure 1;

50 Figure 3 is a side elevation of a portion of the metallic body, certain portions thereof being illustrated in section;

Figure 4 is a transverse sectional view on the line IV—IV of Figure 3;

55 Figure 5 is a perspective view, on an enlarged scale, of a portion of one side of the

truck body illustrated in Figures 3 and 4, 55 and

Figure 6 is a detail view, on an enlarged scale, of a portion of the truck body.

In accordance with the present invention, a truck body of the wood type may be constructed by providing a pair of longitudinally extending I-beams 2 having extending transversely thereof a series of similar beams 3. These beams constitute the supporting members for the truck body, and both the 60 number and location may be varied as required. For securely holding the ends of the transversely extending I-beams or supporting members in the desired position, protecting the same, forming a running board, and a 65 side bumper, there may be provided a metallic covering 4 of sheet material, shaped to extend over a portion of the upper surface of the transversely extending members, and thence across and under the ends of the same 70 in such manner as to embrace or partially enclose them. It will be apparent that this metallic covering not only improves the appearance of the truck body and reinforces the 75 same, but also provides a foot rail or running board conveniently located for use during loading and unloading of the truck. This covering also serves as a side bumper protecting the truck body while in service.

Carried by the metal supporting members 85 above the covering 4, and extending upwardly therefrom are side irons 5 shaped to provide the desired body contour. These side irons are very important and represent a radical departure from the present practice of truck 90 body construction. Each side iron is directly secured to the metal frame in some suitable manner, as by rivets, passing through the covering 4 and the flanges of the transverse members 3. In the preferred embodiment of 95 the invention a side brace is secured to each end of each of the transverse members.

Each of the side irons has a substantially vertically extending portion and an outwardly extending heel or foot 5' by means of which 100 it is easily secured. In transverse section these side irons may be of any desired shape, but preferably I utilize angles, T-sections or channels to provide a main body with a strengthening rib or web projecting therefrom. 105 This insures maximum rigidity.

After all of the side irons are in position, the necessary flooring and side boards 6 may

be applied. By reason of this construction, it will be obvious that in the event of breakage of any of the boards, or when the boards are worn out, a new set of boards may be applied 5 to the metallic framework without any damage thereto, and with a minimum of labor. This makes it unnecessary to disassemble any 10 of the metallic framework each time a body is repaired or made over, and at the same time 15 insures greater strength and rigidity. Furthermore, the use of strap irons within the body is obviated.

In Figures 3 to 6 there is illustrated a slightly modified form of the invention, as 20 applied to bodies of the metallic type. The general sub-frame or framework may comprise longitudinally extending I-beams 2' and transversely extending beams 3', as before described, provided with the metallic covering 4' for the ends thereof. It will thus be apparent that the same general framework is adapted to bodies of either type.

Instead of adding the boards, as in the wooden type body, there is applied a metallic body 7 having the upper side edges 8 thereof bent outwardly and downwardly to provide a smooth upper edge of considerable width. The sides of this body may be partially carried by side irons 9 similar to the irons 5 or 25 30 of the construction shown in Figure 5. In either case they are directly secured to metal, as by rivets, entirely outside of the body.

This metallic body 7 may be constructed to 35 carry the maximum load of heavier materials, such as wet sand and the like. When it is desired to handle lighter materials, it will be apparent that such body would have insufficient capacity. By reason of the broad upper side edge 8, it is possible to easily apply 40 metallic side boards 10 of any desired width for providing the necessary additional capacity. Each of these side boards may comprise 45 a sheet of metal having the lower edge 11 turned outwardly to abut against the side edge 8, and having the upper edge 12 shaped in a manner similar to the edge 8.

As with truck bodies of this general type, it is desirable to provide end gates facilitating the dumping operation. Each body may

be formed with rear standards 13 adapted to 50 carry the end gate, as well understood in the art. Each of these standards is preferably rigidly secured to the truck body 7 by a gusset plate 14 at each side. These gusset plates 55 cooperate effectively with the side boards 10 for holding the same in position, and if desired, bolts 15, passing through registering openings in the side boards and gusset plates respectively, may be provided. This enables 60 the side boards to be quickly placed in position or removed as required by the character of the material being handled.

In addition to serving as a foot support, the covering material 4' also effectively cooperates in either type of body with stakes 16, 65 the turned-in lower portion of the covering material engaging the lower end of each stake and limiting its downward movement.

The advantages of the present invention 70 arise from the provision of a skeleton frame for truck bodies adapted to cooperate either with a body of the wooden or a body of the metallic type, this skeleton frame having a maximum strength and being capable of assembly with a minimum amount of labor. 75

Other advantages of the invention arise 80 from the provision of the side irons 5 or 9 secured entirely outside of the body, attached directly to the metal of the main frame and having outwardly extending feet or heels 85 serving as braces and facilitating attachment.

Still further advantages of the present invention arise from the construction of a metallic body whereby the application of side boards thereto is facilitated. 90

I claim:

A truck body comprising a metallic frame including transversely extending members, a metallic cover extending over the ends, the tops and bottoms of the transversely extending members, the body having side members, and stakes for supporting extension side boards for the body extending through the openings in the tops of the metallic cover and supported on the bottom thereof. 95

In testimony whereof I have hereunto set my hand.

LEO J. STYSLINGER.
